UNITED STATES PATENT OFFICE.

GIUSTO BOGGIO, OF ROYALTON, ILLINOIS.

TOY GUN.

Application filed January 26, 1925. Serial No. 4,748.

To all whom it may concern:

Be it known that I, GIUSTO BOGGIO, a subject of the King of Italy, and resident of the city of Royalton, county of Franklin, 5 and State of Illinois, have invented certain new and useful Improvements in Toy Guns, of which the following is a specification containing a full, clear, and exact description, reference being had to the accompanying 10 drawings, forming a part thereof.

My invention relates to improvements in toy guns and has for its primary object a toy gun which is provided at its muzzle with a figure which is designed to be projected forward upon firing the gun and to return into position when the gun is again cocked.

A further object is to construct a toy gun in which a figure mounted at the muzzle is 20 designed to be projected forward a certain distance and during said projection make several revolutions and finally when coming to rest adapted to hang up-side down.

In the drawings:

25 Fig. 1 is a side elevation of my device; Fig. 2 is a vertical longitudinal fragmental section of the gun showing the various operative parts; and

30 Fig. 3 is an enlarged perspective view of the forward part of the figure support.

In the construction of my device I employ a gun provided with a barrel 4, a stock 5, and a trigger 6. Located within the barrel is a spring 7, its rear end abutting a 35 stop 8. The forward end abuts a disk 9 which is slidably mounted in the barrel 4. Secured to the disk and extending through the spring is a bar 10 which is provided at its rear end with a hook 11; the hook 11 is 40 adapted to engage with a notch 12 carried by the trigger 6. The trigger is pivotally mounted at the point indicated by the numeral 13 and is normally held in forward position by means of a spring 14. In 45 order to prevent the trigger from entering too far, it is provided with a projection 15 which contacts with the forward portion of the slot 16 through which the trigger projects

50 The stock 5 is pivotally mounted to the barrel at the point indicated by the numeral 17 and has passing through it adjacent its upper forward end a pin 18. Pivotally mounted on the pin 18 is a wire loop 19 which is adapted to engage with the hook 11 as will be hereafter described. Secured in

the muzzle of the barrel 4 is a disk 20 which is provided with an elongated slot 21 through which extends the figure support which consists of a flat strip of material 22. 60 This strip is twisted into a spiral as illustrated in Fig. 2 and has secured to its rear end a disk 23. The forward end of the support is looped over as indicated by the numeral 24 which forms a socket for the reception of a figure 25. This figure can be of any desired shape, preferably being either a bird, or a rabbit, or a squirrel.

Located between the disks 20 and 23 and surrounding the strip 22 is a coil spring 26, 70 the purpose of which is to draw the strip backward when the gun is cocked.

The loop 24 may be made resilient so as to permit the figure 25 to be held therein by friction or the figure may be secured 75 therein by any well known fastening means.

The operation of my device is as follows:

In order to cock the gun the stock 5 is bent downward, this permits it to pivot at 80 the point 17 and cause the loop 19 to engage with the hook 11 and draw the bar 10 backward thus compressing the spring 7. When the gun is cocked the hook 11 rests in the notch 12 as indicated in Fig. 2. During this time the spring 26 has expanded and drawn the twisted or spiral strip 22 backward causing the figure 25 to assume the position shown in Fig. 1. Upon pulling back on the trigger 6 the hook 11 is 85 released; this permits the spring 7 to expand and being a much heavier spring than the spring 26 will force the disk 23 forward. The forcing of this disk forward causes the strip 22 to travel through the slot 95 21 thus imparting a rotary motion to the strip, which in turn is imparted to the figure causing it to make one or more side-wise revolutions.

The twisting of the strip is so arranged 100 that the figure will stand upright when the gun is cocked and when discharged will hang head down. Immediately upon cocking the gun the figure will again assume the position shown in Fig. 1.

This hanging down of the figure after the gun has been discharged is accomplished by making the twisted strip in two pieces and pivoting the same at the point indicated by the numeral 27; thus when this strip is projected forward from the muzzle, the strip can bend at this point and hang

down below the muzzle of the gun thus giving the figure the appearance of dropping after being shot.

Having fully described my invention, 5 what I claim is:-

- 10 1. A device of the class described comprising a gun having a trigger, a figure, a support formed of two members pivotally connected together for said figure extending into said gun, means located in said gun and operable by said trigger for moving said figure and support forward a predetermined distance whereby said figure and the forward end of said support hang below the gun, and means for returning said support and figure to their original position when said gun is cocked.
- 15 2. A device of the class described comprising the combination with a toy gun having a cocking and discharging means, of a spiral support located within the barrel of said gun and extending beyond the muzzle of said gun, said support adapted to be projected from said muzzle a predetermined distance, means located within the muzzle of said gun and engaging with said support for rotating the same during its projection, a figure secured to said support outside of and adjacent the muzzle of said gun, and means

for returning said support and figure to 30 their original position simultaneously with the cocking of said gun.

3. A device of the class described comprising a gun having a barrel and a stock, a slotted disk secured in the muzzle of said barrel, a spiral supporting strip extending through said disk, means carried by said strip and located within said barrel for limiting the forward movement of said strip, a spring located within said barrel, 35 means for contracting said spring, means for holding said spring in contracted position, means for releasing said spring, and means located adjacent the forward end of said spring and adapted to contact with the spiral strip for moving the same forward, whereby said spiral strip is given a longitudinal rotary movement.

4. The device of claim 3 in which the spiral supporting strip is hinged intermediate its length whereby the forward portion of said strip will assume a position at an angle to the remainder of the strip as soon as the pivoted point has passed beyond the slotted disk.

In testimony whereof I have signed my name to this specification.

GIUSTO BOGGIO.
